SOLE FOR BOOT OR SIMILAR FOOTWEAR ARTICLE

Abraham Messinger, Larchmont, N.Y., assignor to Vylt Corporation, New York, N.Y.

Filed Oct. 6, 1961, Ser. No. 67,001

Term of patent 14 years

(Cl. D7—5)

FIG. 1

FIGURE 1 is a bottom plan view of the sole for a boot or similar footwear article embodying my new design;

I claim:

The ornamental design for a sole for a boot or similar footwear article, as shown.
